UNITED STATES PATENT OFFICE.

WILLIAM H. BRIGGS AND GEORGE M. CLARK, OF CHICAGO, ILLINOIS.

SIGNAL-LANTERN AND FLAG HOLDER.

SPECIFICATION forming part of Letters Patent No. 340,090, dated April 20, 1886.

Application filed April 14, 1885. Serial No. 162,189. (No model.)

To all whom it may concern:

Be it known that we, WILLIAM H. BRIGGS and GEORGE M. CLARK, citizens of the United States, residing in Chicago, in the county of 5 Cook and State of Illinois, have invented a new and useful Improvement in Signal-Lantern and Flag Holders, of which the following is a specification.

Our invention relates to holders for displaying signal-lanterns and flags on railway cars, 10 locomotives, and other analogous places. Our object therein has been to combine in one device both a lantern-holder and a flag-holder, so constructed that it can be adjusted for either 15 use readily and quickly; and the invention consists in certain novel and useful arrangements, combinations of parts, and peculiarities of construction fully described hereinafter.

In the drawings, which form a part of this 20 specification, Figure 1 is a front elevation of the holder when arranged for use with the flag. Fig. 2 is a side view of the device in the same position. Fig. 3 is a side view showing the holder in position to receive a lantern. Fig. 25 4 is a top view, the parts being in the same position as in Fig. 3. Fig. 5 is a partial vertical section on line 5 5 of Fig. 4. Fig. 6 is a partial front view of the attaching-plate. Fig. 7 shows the arrangement for locking the arms 30 to prevent the removal of the lantern; and Fig. 8 is a partial central vertical section showing the parts in the position indicated by Fig. 3.

In the drawings, A represents the attaching- 35 plate, provided with an outwardly-extending bracket, a, which receives a pintle, a', upon which the apparatus may be swung horizontally, and to which pintle the holding devices are hinged at a² in such manner as to enable 40 them to swing vertically.

The main feature of the holder proper is the 45 series of radiating arms or supports B B' B², forming a spider-like device. One arm, B, of this series is hinged, as already stated, at a², and this arm forms the support for the radiating arms and the other parts borne thereon. Said arm also carries a pin, b, by means of 50 which the apparatus, when used as a lantern-holder, is positioned upon the plate A, said pin entering such one of the openings a³ in the bracket a as desired. The pin b also serves to

support the radiating arms when lowered to the horizontal position by the engagement of its shoulder a⁴ with the bracket a. Each of the radiating arms is slotted, and in such slots 55 are inserted movable hook-carrying slides C C', each of which is provided with a pin, c, entering eccentric slots d in the rotatable plate D. Through the movements of this plate the slides are moved in or out, as desired, according as the lamp is to be secured or released. When secured, the hooks c' lap over the base-plate of the lantern, the outline of which is indicated by dotted line r in Fig. 4.

The plate D is turned with its central pivot, 60 d', the latter having a bearing in the center of the plate forming the base or junction of the radiating arms and carrying upon one extremity the flag-socket E and a disk, E', and at the other end a button, F. The disk 65 E' is partially ratchet-faced and provided with a shoulder, f, and with such ratchet and shoulder a spring-pawl, G, supported upon a connecting-bar, g, engages, as required, to secure the parts against turning. This engage- 70 ment is such that the rotation is permitted in the direction in which the parts move when the slides are to be drawn toward the center; but movement in the opposite direction is re- 75 sisted, and when the latter movement is de- 80 sired the pawl must be pressed upon by the thumb and caused to release its hold.

When the device is to be used as a lantern- 85 holder, the radiating arms are lowered to that one of the horizontal positions desired, and the lantern placed thereon, and the hooks are then drawn up until the lamp is fastened. The pawl will now prevent any accidental slipping back of the hooks; but if it is desired to lock them absolutely it can be done by pass- 90 ing any suitable locking device through that one of the openings c' in the depending flange c upon the under side of some one of the slides, say C, registering with the passage be- 95 tween the two depending projections c' upon the radiating arm in which the slide C is car- ried. It will be noticed that in adjusting the slides the flag-socket may serve as a grasp for turning the eccentrically-slotted plate through which the hooks are actuated.

When it is desired to use the device as a 100 flag-holder, the radiating arms are raised to

the vertical position with the button F in position to enter the opening f' in the plate A, and the flag-socket is then rotated until it stands vertical. This brings the button into 5 locking engagement with the plate A, the shoulders f² upon the button standing at either side thereof, as illustrated in Fig. 5, and at this time also the pawl will be in engagement with the shoulder f of the disk, as indicated 10 at Fig. 1, thereby locking the socket against any rotation. This Fig. 1 indicates the position of the parts when used as just described.

Of course the slides are provided with means for securing them in the radiating arms, and 15 we employ for this purpose in the case of slides C' C² buttons i, attached to the slides near their outer ends and spanning the slot in the radiating arms. In the case of the slide carrying the depending flange a lateral pin, i', is secured in said flange, and in order that this 20 slide may be inserted in the radial arms a lateral enlargement, i², is made in the slot of the arm in such position that said pin will not enter it in the ordinary movements of the 25 slide. The assembling of the parts with the eccentric disk overlapping the ends of the slides aids in confining them in their respective slots. They might of course slide in dovetail grooves, if that were deemed preferable.

m m indicate stops upon the plate A, acting to prevent interference between the plate and the hooks and pins upon the slides.

When not in use, the holding devices proper 35 are preferably folded up against the attaching-plate, as shown in Figs. 1 and 2.

While we have shown three radial arms, we do not wish to be limited to that feature in terms, as it is obvious that any number of 40 radial arms convenient for the purpose could be used instead. It is also obvious that the arms may be strengthened by connecting them together otherwise than at their junction or base.

45 We claim—

1. The signal-lantern holder consisting of a supporting-plate, in combination with a spider hinged to said plate and having movable hook-carrying slides, and the eccentrically-slotted plate engaging with and actuating the slides, substantially as specified.

2. The signal-lantern holder consisting of a supporting-plate, in combination with a spider hinged to said plate and having movable hook-carrying slides, a rotatable eccentrically-slotted plate engaging with and moving the slides, and a pawl and ratchet for securing the plate against rotation, substantially as specified.

trically-slotted plate engaging with and moving the slides, and a pawl and ratchet for securing the plate against rotation, substantially as specified.

3. The combination of a supporting-plate, 60 a hinged lantern-holder adapted to fold up against the plate, a lock for securing it in the folded position, and a flag-socket borne upon the lantern-holder, substantially as set forth.

4. The combination, in a lantern-holder, of 65 a series of radial arms, slides in said arms provided with hooks for engaging the lantern and having pins c, a rotating slotted plate pivoted upon said arms and engaging said pins, a ratchet-disk on the same pivot and attached to said plate, and a spring-pawl pivoted to said arms and engaging said disk, substantially as specified.

5. The combination, in a lantern-holder, of 70 a series of radial arms, in combination with slides working in said arms and provided with hooks c' and pins c, a rotating slotted plate pivoted upon said arms and engaging all said pins, one of said slides having also a perforated depending flange, and the arm in 75 which the same is located having depending projections, by means of which flange and projections all the slides may be locked, substantially as specified.

6. The combination of plate A, having 80 opening f', with the swinging holder having a retaining-button to enter said opening, and the flag-socket secured to the same pivot with said button, substantially as specified.

7. The plate A, having opening f', the 85 swinging holder having a retaining-button to enter said opening, and a flag-socket, in combination with a spring-pawl carried on the holder and a locking-ratchet, the socket, ratchet, and button being fast upon the same 90 pivot, substantially as specified.

8. The combined lantern and flag holder 95 consisting of the attaching-plate A, provided with the locking-opening, in combination with a spider having one of its arms hinged 100 to said plate, hooks for securing the lantern attached to the arms of said spider, a retaining-button mounted on said spider, and a socket attached to the shank of said button, substantially as specified.
